US0D1087097S

(12) **United States Design Patent** (10) Patent No.: **US D1,087,097 S**
(45) Date of Patent: ** Aug. 5, 2025

(54) **DATA CAPTURE DEVICE**

(71) Applicant: **ZEBRA TECHNOLOGIES CORPORATION**, Lincolnshire, IL (US)

(72) Inventors: **Steven D. Sieckowski**, Port Jefferson, NY (US); **Benjamin H. Stibal**, Patchogue, NY (US)

(73) Assignee: **Zebra Technologies Corporation**, Lincolnshire, IL (US)

(**) Term: **15 Years**

(21) Appl. No.: **29/951,227**

(22) Filed: **Jul. 8, 2024**
